AUTOMATICALLY-DEFORMABLE BALLOON.

1,031,148.

Specification of Letters Patent.

Patented July 2, 1912.

Application filed April 14, 1908. Serial No. 426,942.

To all whom it may concern:

Be it known that I, ATTILIO RANZA, engineer, of 41 Via della Vite, Rome, Italy, have invented certain new and useful Improvements in Automatically-Deformable Balloons, fully described and represented in the following specification and the accompanying drawings, forming a part of the same.

In the net suspension types, used up to the present, the net surrounds only the upper part of the balloon, leaving the lower part uncovered and the form of said lower part undergoes the continuous changes in accordance to the fluctuations of the volume of the gas, and when the balloon is completely filled up it becomes stretched out while its resistance is not increased by the action of the net, as it happens in the upper hemisphere. Moreover the deformation of the lower hemisphere causes various inconveniences especially when the balloon is exposed to a wind of a certain intensity.

The object of this invention is a disposition in the suspension which allows the distribution of the pressure of the net upon both the hemispheres, viz., upon the whole surface of the balloon, whatever may be the actual degree of its distention. By the adoption of such a system of suspension it is possible to reduce the strain in the gas bag and also to prevent the inconveniences of the wind upon the part of the balloon not distended because, as it will be seen hereinafter, all parts of the envelop remain constantly distended.

The use of this type of balloon is particularly advantageous whenever recording apparatus must be carried up or passengers are to be transferred up or down hill along conveniently inclined ropes, between points at considerable differences of height, because this type of balloon allows the variation of the volume depending upon the variations of the altitude, without becoming flaccid.

In the annexed drawings Figures 1 and 2 show diametral sections illustrating two different forms of construction of a spherical balloon in accordance with this invention and Fig. 3 shows another form of construction with the envelop in section which permits the passenger to control at leisure the pressure of the net upon the lower hemisphere.

As it may be seen in Fig. 1 the envelop

—1— is totally inclosed within the net —2— formed by ropes preferably arranged along the meridians and the parallels. At the top the net is fastened to a ring —3— lying externally on the envelop and surrounding the upper opening of a tube —4— which extends through the whole height of the envelop. Inside said tube passes the cable —5— to which the balloon is moored or to which is hung the weight and the upper end of which is fastened to the ring —3—. Evidently when the volume of the gas decreases, the cable —5— pulls downward the ring —3— and reduces the volume of the envelop thus keeping both the upper and the lower parts of the balloon distended. The result is that the wind cannot have a great action as it cannot cause a deformation of the lower part, still distended, and thus a stability is obtained which it is not possible to secure by the usual system of fastening. The stability can still be increased by means of a crown —6— formed by a circular zone or by radial sectors kept in the proper place by means of stay wires —7— which join all together at the point —8— of the cable. Thus is obtained a stability which compares well with the stability of a kite.

Whenever the balloon is of a small volume it may be convenient to omit the net and to connect the mooring cable —5— to a ring or crown made of strong fabric stitched to the stuff of the envelop on the interior side of the upper hemisphere, as it may be seen, for instance, in Fig. 2, or even to use, instead of the free net, ropes or linen strips stitched or glued to the surface of the envelop. Fig. 2 shows also how instead of the interior tube —4— the envelop may be provided with an extensible bellow-like tube —9—, and the lower end —10— of which is hermetically stuck to cable —5— which, then, leads as usual to the ring —3— of the upper hemisphere.

Whenever the volume of the gas decreases, cable —5— is pulled down and the folded tube —9— becomes longer. The said extensible tube can also be used in combination with the net-suspension shown by Fig. 1 and likewise the form of construction of Fig. 2 can be provided with the circular crown —6— which is intended to give a greater stability to the system in the aforesaid way illustrated by Fig. 1.

In all the forms of construction described above the pressure of the net on the envelop is automatically controlled and maintained by the variations of volume of the gas, but 5 in the case of balloons of a considerable volume, intended to carry up passengers it may be advantageous to have a means to control the gas pressure at will according to circumstances. To obtain this result it 10 will suffice to provide the net with a row of suspension ropes —12— extending to one of the blocks —13— of a tackle the other block of which is fixed to the cable —5— so that the tension rope —16— will be under the 15 hand of the aeronauts, who consequently can, by regulating the tension of the ropes of the tackle, make the crown of ropes —12— support a portion of the load of the cable —5— of which they may deem convenient to discharge the lower hemisphere 20 of the balloon.

I claim—

1. In balloons of variable capacity the combination of a reefing net completely surrounding the balloon, a tube provided in the interior of the balloon, a connecting ring where the net is fastened, resting on the top of the balloon around the upper opening of the diametral tube, a cable passing 25 through said tube and fixed at the upper end to the ring and having its remaining portion free from connection with the lower hemisphere.

2. In balloons of variable capacity the combination of a reefing net completely surrounding the balloon, a tube provided in the interior of the balloon, a connecting ring where the net is fastened resting on the top 30 of the balloon, around the upper opening of the diametral tube; a mooring cable passing through said tube and fastened at one end to the ring, a circular steadyng crown fastened around the lower hemisphere of the balloon, in order to increase the stability 35 against the action of the wind, and stay wires fastened to the edge of the crown and

joining together in a point connected to the mooring cable.

3. In balloons of variable capacity the combination of a reefing net completely surrounding the balloon; a tube provided in the interior of the balloon; a connecting ring, resting on the top of the balloon around the upper opening of the tube; a mooring cable passing through said tube and fastened at 50 one end to the ring; a circular steadyng crown fastened to the net around the lower hemisphere of the balloon; stay wires fastened to the edge of the crown and joining together in a point; a tackle connecting said point to the mooring cable and the tension rope of which ends in a car suspended to the mooring cable, so that the passengers may within certain limits control the proportion of pressure of the net on the upper 55 and lower hemisphere of the balloon.

4. In balloons of variable capacity, the combination of a reefing net completely surrounding the balloon; a tube provided in the interior of the balloons; a connecting ring 60 resting on the top of the balloon around the upper opening of the diametrical tube, a reefing cable passing through said tube and fastened at its upper end to the ring; a mooring cable adapted to be fastened at its 65 lower end to the ground; a circular steadyng crown fastened to the net around the lower hemisphere of the balloon; stay wires fastened to the lower hemisphere of the balloon and joining together in a suspension 70 ring; a tackle, the tensioning rope of which ends within the car, and suitable connections between the car, the suspension ring, the mooring cable, the reefing cable and the blocks of the tackle, so that the passengers 75 may control at will the pressure of the net on the lower hemisphere of the balloon.

ATTILIO RANZA.
